(57) **CLAIM**

The ornamental design for a front combination lamp for a motor vehicle, as shown and described.

DESCRIPTION

FIG. 1 is a front perspective view of a front combination lamp for a motor vehicle showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The mirror image of my design is also claimed but not shown.

1 Claim, 7 Drawing Sheets
